UNITED STATES PATENT OFFICE.

WARREN S. GAUNTT, OF KANSAS CITY, MISSOURI.

DESIGN FOR A TIRE-TREAD.

58,478.

Specification for Design.

Patented July 26, 1921.

Application filed July 29, 1920. Serial No. 399,911. Term of patent 14 years.

To all whom it may concern:

Be it known that I, WARREN S. GAUNTT, a citizen of the United States, residing at Kansas City, in the county of Jackson and State of Missouri, have invented a new, original, and ornamental Design for Tire-Treads, of which the following is a specification, reference being had to the accompanying drawing forming part thereof, in which—

Figure 1 is a front elevation of a tire tread embodying my new design.

Fig. 2 is a broken cross section thereof.

I claim:—

The ornamental design for a tire tread as shown.

WARREN S. GAUNTT.
